H. L. McMILLAN

AUTOMATIC SEWAGE SCREEN RAKE

Filed April 28, 1923

Inventor:

Henry L. McMillan

By *Frank Wilson*

UNITED STATES PATENT OFFICE.

HENRY L. McMILLAN, OF CHICAGO, ILLINOIS.

AUTOMATIC SEWAGE-SCREEN RAKE.

Application filed April 28, 1923. Serial No. 635,249.

To all whom it may concern:

Be it known that I, HENRY L. McMILLAN, a citizen of the United States, residing at Chicago, in the county of Cook and State 5 of Illinois, have invented certain new and useful Improvements in Automatic Sewage-Screen Rakes, of which the following is a specification.

This invention relates to apparatus for 10 automatically removing the floating and submerged material and articles from a flowing stream of sewage, and while capable of use for other purposes, is particularly adapted for freeing storm sewers, and the 15 like, from solid material and articles which would have a tendency to eventually clog the water course into which the sewer discharges, or to interfere with subsequent treatment of the sewage.

One of the primary purposes of this invention is to provide an apparatus of the character indicated which will be entirely 20 automatic in its operation, and which will normally operate continuously; but should 25 it accidentally become clogged, no damage to the apparatus will ensue, but the apparatus will remain idle until the obstruction has either cleared itself, or been removed, 30 whereupon the operation of the apparatus will be automatically resumed.

Another purpose is to provide an apparatus which will cause the rake to travel in a 35 desirable path, preferably generally elliptical in shape, so that the rake will enter the sewage stream some distance above or upstream from the screen, whereupon it will be dragged along the floor of the sewer toward the screen, thence upwardly along the 40 screen, at the upper end of which the material removed will be dumped upon a platform, whereupon the rake will be moved above the line of the sewage level in an upstream direction to the point where it is again lowered into the stream.

A further object is to provide an apparatus in which all of the rake moving and operating parts will be disposed entirely above 45 the sewage level in the sewer, so that they will not be affected by variations in the level or by floating or submerged objects in the sewage, or damaged by continued contact with the sewage or solid gritty matter carried along by the sewage, and will further-

more be accessible at all times for inspection and repairs, if necessary, without dewatering 55 the chamber in which the apparatus operates.

Still another object is to provide an apparatus which will be simple in construction, reliable in operation, and strong, substantial 60 and durable in use.

Other objects of the invention should be readily appreciated as the same becomes better understood by reference to the following description, when considered in connection 65 with the accompanying drawings.

Referring to the drawings:

Fig. 1 is a longitudinal sectional view through a sewer, showing my invention in side elevation;

Fig. 2 is a fragmentary sectional view through the sewer screen, showing the rake in cooperative relation thereto; and,

Fig. 3 is a detail of one of the valve operating mechanisms.

Referring to the drawings more in detail, reference character 5 indicates generally a sewer provided with an enlarged chamber 6 having throughout a portion of its length a floor or ledge 7 above the sewage level, upon 80 which the solid matter removed from the sewage is deposited, and from which it may be removed through a top or side door (not shown).

A screen, indicated generally by reference 85 character 8, comprising a series of parallel bars 9 extending in an inclined direction from the edge of the ledge 7 to the floor of the sewer, extends across the sewer to intercept floating or submerged material or articles carried along by the sewage stream, which flows in the direction indicated on the drawings by the arrows.

A heavy rake 11, provided with parallel 95 teeth 12, adapted to enter between the screen bars 9, as illustrated in Fig. 2, is adapted to be manipulated to remove the objects intercepted by the screen and deposit them upon the ledge 7. The tines of the rake are connected by one or more rods 13, and are maintained in spaced relation by tubes, rollers, or blocks 14 carried by the rod between adjacent tines, and these members, during the travel of the rake upwardly along the screen, ride upon the upper edges of the 100 screen bars, absorbing the wear between the 105

rake and screen, and limiting the projection of the rake teeth through the screen between the bars. It should be understood that the term "rake" is employed in a generic sense, and is not restricted to a large tined implement, as illustrated, but comprehends instruments having extremely fine teeth or even bristles, such as might be employed in brushes revolving or otherwise for cleaning fine screens or other surfaces.

Various means, mechanically, pneumatically, or hydraulically actuated, may be employed to manipulate the rake, but I have shown herein, for illustrative purposes, a simple, compact, and efficient hydraulic apparatus, which will now be described as illustrative of the principles of my invention.

To the upper end of the rake 11 there is attached one end of a cable 15, and to the other end of the rake at the base of the teeth 12 there is attached a second cable 16, it being understood, of course, that these cables may be divided and each attached to the rake at a plurality of points, to preclude tipping of the rake, and that the cables may be made of hemp, or in the form of chains, but preferably are heavy wire cables, as shown.

The apparatus for manipulating these cables is preferably mounted above the upper floor 17 of the chamber 6, and while the apparatus is shown somewhat diagrammatically, and partially in section, it should be manifest that it is substantially mounted and supported upon suitable supporting structures. The motive apparatus by which the cables are manipulated comprises in the present instance a pair of cylinders 18 and 19, in which the pistons 21 and 22 are arranged to reciprocate, respectively. It will be observed that the cylinder 19 is substantially one-half the diameter and twice the length of the cylinder 18, although obviously other desired relative proportions might be employed. The outer end of the piston rod 23, connected with the piston 22, is attached to the cable 16, which is trained over a pulley 24 and a pulley 25, disposed substantially above the up-stream end of the desired path of travel of the rake. The other piston rod 26, connected with the piston 21, carries at its outer end a pulley 27, over which the cable 15 is trained, the end of this cable being anchored to a fixed anchor block 28. From the pulley 27, the cable 15 passes over a pulley 29, thence downwardly through the floor 17 and over a second pulley 31, disposed above and a limited distance downstream from the down-stream end of the desired path of travel of the rake. It should be understood that the pulley 27 carried by the piston rod 26 is used only to permit a short cylinder 18 to be used instead of one smaller in diameter

and substantially twice as long, and that the same expedient may be utilized in the case of cylinder 19 and piston rod 23 to afford the use of a shorter and larger cylinder than is herewith shown. Furthermore, pulleys 27 and 28 may be used in duplicate, or otherwise, to afford shorter piston movement for the same amount of rake travel, or pulley 27 may be omitted and cable 15 attached directly to the piston rod 26.

The pistons 21 and 22 are hydraulically actuated to draw in and pay out their respective cables by water from a supply pipe 32, connected with any suitable source of water supply under pressure. A control valve 33 for the cylinder 19 is shown as being of the usual four-way type, although a slide valve or other preferred type of reversing valve might be used, the water supply being furnished thereto through a branch pipe 34, and the exhaust being delivered therefrom through a branch 35 to the main exhaust line 36. When the valve is in the position shown in Fig. 1, water from the branch 34 will be delivered through the valve and through the pipe 37 to the left-hand end of the cylinder, while simultaneously the exhaust from the cylinder will be discharged through the pipe 38, the valve 33 and the branch 35 into the exhaust line. When the valve is moved to reverse position, as will be later explained, pipe 38 becomes the supply pipe to the cylinder, and pipe 37 the exhaust pipe therefrom.

Cylinder 18 is provided with a similar control valve 39, adapted to receive water from the supply pipe 32 through the branch 41. From the valve the water is delivered when the parts are in the position shown in Fig. 1, through the pipe 42 to the cylinder, the exhaust therefrom being discharged through the pipe 43 to the valve 39, and thence through the exhaust branch 44 into the exhaust line 36. When valve 39 is reversed, pipe 43 becomes the supply pipe for the cylinder and pipe 42 conducts the exhaust from the cylinder to the valve.

For the purpose of operating the control valve 39, which controls the direction of movement of the piston 21, the piston rod 23 is provided with an upwardly extending actuating finger 45, adapted upon movement toward the right, viewing Fig. 1, to engage and swing the arm 46, which is connected by a link 47 with an arm 48, fixed on the projecting axis of the valve 39. Upon reverse movement of the finger 45, this finger will directly engage the arm 48 and swing the valve 39 into the position shown in Fig. 1. In order that the finger 45 may idly pass the arm 48 in its movement toward the right, this arm is equipped at its lower end with a pivoted extention 49 (Fig. 3), adapted, as will be apparent from this figure, to permit movement of the finger 45 to the right with

out actuating the arm, but adapted to be disposed in the path of movement of this finger to the left to swing the arm 48 in a clockwise direction upon movement of the finger to the left.

Control valve 33 for the cylinder 19 is adapted to be actuated by a finger 51, mounted upon the outer end of the piston rod 26, and when this finger approaches its extreme left position, as shown in Fig. 1, it engages and swings to the left an arm 52 fixed on the projecting axis of the valve 33. When the finger approaches the limit of its movement in the reverse direction, it engages a pivoted arm 53, which, through a link connection 54 with the arm 52, swings this arm in the opposite direction to reverse the valve 33. Obviously, other valve arrangements and other means for operating the reversing valves than the specific form illustrated are comprehended within the scope of my invention.

Assuming the parts to be in the position shown in full lines in Fig. 1, it will be observed that valve 39 is positioned to deliver water under pressure to the cylinder 18 through the pipe 42, thereby forcing the piston 21 to the limit of its travel toward the left. As the finger 51 approached the limit of its travel toward the left, the arm 52 was actuated thereby to reverse the valve 33, so that, as shown in Fig. 1, water under pressure is just beginning to be delivered through the pipe 37 to the left-hand end of the cylinder 19. The cable 15 being entirely paid out, and the cable 16 being entirely drawn in, the rake 11 will be suspended from these cables above the water level in the sewer in substantially the full line position shown in Fig. 1. As the piston 22 now moves toward the right, the cable 16 will be paid out, thus lowering the rake into the sewage stream at a point considerably up-stream from the screen 8. The cable 16 will continue to be paid out as the piston 22 moves toward the right, and when the piston approaches the limit of its movement, finger 45 will engage the arm 46, swinging the same in a counter-clockwise direction to reverse the valve 39. Water will thereupon be delivered to the left-hand end of cylinder 18 through the pipe 43, and exhausted from the cylinder through the pipe 42. Movement of the piston 21 toward the right will thereupon draw in the cable 15, and since the cable 16 is slack, the rake will be drawn first along the floor of the sewer to the base of the screen, and then upwardly along the screen to the upper end thereof. The rake will be carried above and downstream with respect to the upper end of the screen before the piston 21 reaches the limit of its movement toward the right, and since pulley 31 is mounted considerably to the left of the screen, the rake, when it clears the upper

end of the screen, will travel for a limited distance to the left along the ledge 7, so as to carry the material brought up by the rake well onto the ledge and away from the screen. As the piston 21 approaches the limit of its travel, the finger 51 will engage the arm 53 and swing the same to the right, thereby reversing the valve 33. As the result of this reverse action, the piston 22 will begin to travel toward the left, thereby exerting through the cable 16 a pull upon the rake 11 toward the pulley 25, which action will lift the rake above the ledge 7 into the position shown in dotted lines in Fig. 1, thereby freeing the rake from the material deposited on the ledge. When the piston 22 is moved a short distance toward the left, the finger 45 will engage the pivoted extension 49 of the arm 48 to thereby swing this arm toward the left and reverse the valve 39, which reverse action causes the piston 21 to begin to travel toward the left, paying out the cable 15, while finger 45 slips past the end of extension 49 and continues its travel toward the left. The cable 16 is at the same time being drawn in, and the rake therefore, suspended by two cables, will be carried from the dotted line position shown in Fig. 1 back to the full line position shown therein, this movement being entirely above the sewage level in the sewer. When both pistons have reached their extreme left position, the valve 33 will have been reversed by the finger 51, and the cycle of movement of the rake just described will be repeated. The orbit or path of movement of the rake head is indicated by the dotted orbit 55, while the path of the upper end of the rake is indicated by the orbit 56. These orbits are of course illustrative merely, since they will vary in accordance with differences in the length of the cables, the relative speed at which they are drawn in and paid out, and also with differences in the relative weights of the head and the upper end of the rake.

It will be apparent from the foregoing that the rake is caused to travel in a generally elliptical orbit, which enables the rake to gather material and objects upon the floor of the sewer, and also that intercepted by the screen, and deposit the same upon the ledge 7, clear of the upper end of the screen. Furthermore, the timing of the cable movements is such that the rake is dumped or freed from the material and is returned up-stream but entirely clear of the sewage to the desired point where it is again lowered into the stream.

The apparatus for manipulating the rake is disposed entirely clear of the sewage stream, where it is accessible at all times for inspection and repairs, and is not subject to injury or damage by heavy articles or material carried by the sewage, or by submersion, and the chamber in which the

rake operates does not require dewatering to enable the inspection or repair of any part of the apparatus. Furthermore, should the rake become clogged by excessively large 5 objects, such as floating logs or the like, or should the tines of the rake become jammed in the sewer with material from the sewage, no injury to the mechanism can result, since the parts will simply remain stationary until 10 the rake, as the result of continued pull thereon, frees itself, or the obstruction has been otherwise removed, or the rake has been lifted from the screen by manually reversing the valve 33, thereby causing the cable 15 16 to be drawn in, whereupon the operation of the apparatus will be automatically resumed. The apparatus is entirely automatic in operation, and will operate for an extended period of time without supervision 20 or attention.

The details of construction may obviously be varied within wide limits without departing from the essence of the invention, as defined in the following claims.

25 I claim:

1. In an apparatus of the character described, the combination of a sewer, a screen therein, a rake, a pair of cables attached to the ends of said rake respectively, and means 30 for drawing in and paying out said cables whereby said rake is caused to move forwardly along the floor of said sewer towards the screen, upwardly along the screen, forwardly beyond the upper end of said screen, 35 then backwardly above the water level in the sewer to a point remote from the screen and then downwardly to the floor of said sewer, the movement of the rake being in a generally elliptical path the major axis of which is substantially horizontal.

40 2. In an apparatus of the character described, the combination of a sewer, a screen therein, a rake, and means for supporting and moving said rake in a substantially horizontal elliptical orbit whereby the rake is caused to travel toward the screen along the bottom of the sewer, thence upwardly along the screen, then forwardly beyond the upper end of the screen and then rearwardly to a point remote from the screen at which point it is lowered to the floor of the sewer.

45 3. In an apparatus of the character described, the combination of a sewer, a screen therein, a rake, a cable attached to the front end of the rake, a second cable attached to the rear end of the rake, said rake being entirely guided in its movements by said cables, and means for actuating the cables so as to cause the rake to move along the floor 50 of the sewer to the lower end of the screen, thence upwardly along the screen, then forwardly beyond the upper end of the screen and then rearwardly and downwardly to the starting point, the path of travel of said

rake being in a substantially horizontal elliptical orbit.

4. In an apparatus of the character described, the combination of a sewer, a screen therein, a rake, a pair of cables attached to the ends of said rake respectively, pulleys 70 forwardly and rearwardly of the path of travel of the rake over which said cables are respectively trained, and means for drawing in and paying out said cables over the pulleys to cause the rake to travel along the floor of the sewer to the screen, thence upwardly along the screen, thence forwardly beyond the screen where the material collected by the rake is dumped, thence rearwardly above the water level in the sewer and then downwardly to the floor of the sewer.

5. In an apparatus of the character described, the combination of a sewer, a screen therein, a rake, and means above the sewage level including a pair of cables attached respectively to the front and rear ends of the rake and wholly supporting the rake whereby 85 said rake is moved upwardly parallel with and in proximity to said screen, then rearwardly above said sewage level, and then downwardly to the sewer floor, and then forwardly along said floor to the base of said screen.

6. In an apparatus of the character described, the combination of a rake, a plurality of cables attached to said rake at the front and rear ends thereof respectively, guiding pulleys for said cables mounted above and at each end of the path of travel of said rake, and means for automatically drawing in and paying out said cables over said pulleys in predetermined timed relation to thereby cause said rake to travel in a generally elliptical orbit the major axis of which extends substantially horizontally.

7. In an apparatus of the character described, the combination of a sewer rake, a plurality of cables attached thereto near the opposite ends thereof and entirely supporting the rake, pulleys over which said cables are trained, and hydraulic means for automatically manipulating said cables to cause said rake to travel bodily in a generally horizontal orbit.

8. In an apparatus of the character described, the combination of a sewer rake, a pair of cables from which said rake is suspended, a pair of hydraulically actuated pistons to which said cables are respectively connected, and automatic controlling means for causing said pistons to reciprocate in predetermined timed relation to move said rake in a generally elliptical path.

9. In an apparatus of the character described, the combination of a sewer rake, a pair of cables by which said rake is suspended, a pair of hydraulically operated pistons to which said cables are respectively

connected, a control valve for each piston, and means operated by each piston for actuating the control valve for the other piston.

10. In an apparatus of the character described, the combination of a sewer rake, a pair of cables from which said rake is suspended, a pair of hydraulically operated pistons to which the cables are respectively connected, control valves for the respective 10 pistons, and means movable with each piston for reversing at a predetermined point in

its travel the control valve for the other piston.

11. In an apparatus of the character described, the combination of a pair of hydraulically operated pistons, a control valve for each piston, means actuated by each piston for operating the control valve for the other piston, a sewer rake, and connections between said rake and said pistons whereby 20 said rake is manipulated.

HENRY L. McMILLAN.
